UNITED STATES PATENT OFFICE.

ERNEST W. SAUERMAN, OF CHICAGO, ILLINOIS.

DELIVERY MECHANISM FOR PRINTING-PRESSES AND THE LIKE.

1,285,410.

Specification of Letters Patent. Patented Nov. 19, 1918.

Application filed July 31, 1917. Serial No. 183,693.

To all whom it may concern:

Be it known that I, ERNEST W. SAUERMAN, a citizen of the United States, residing at Chicago, in the county of Cook and State 5 of Illinois, have invented certain new and useful Improvements in Delivery Mechanisms for Printing-Presses and the like, of which the following is a specification.

The present invention has to do with certain improvements in delivery mechanisms for use in conjunction with printing presses and the like. The delivery mechanism to which the present invention relates is so constructed that the printed sheets coming 10 from the press will be stacked or piled up in a certain order or sequence with respect to other intermediate or smut sheets, so that the wet sheets coming from the press will not come directly into contact with each 15 other, but, on the contrary, will be separated by the intermediate smut sheets. The constructions and features of invention to be herein disclosed are very well adapted for use in connection with printing presses 20 which print or stamp the windows on sheets used in the making of one-piece window envelops and the like, and for purposes of convenience I have illustrated and will describe the features of invention as applied to a 25 press which is used for this purpose. However, I wish to make it clear that, in so doing, I do not limit myself to the use of the said features of invention on a printing press for this purpose, inasmuch as the said features will be found applicable and very desirable for use in connection with presses 30 used for many other classes of work.

In the manufacture of one-piece window envelops, it is the practice to make use of 40 a cylinder type press, in which the oil or grease spots are printed on large sheets in such relationship to each other that the said sheets may be cut up into envelop blanks with the windows located at the proper 45 points in said blanks. A similar operation is followed in the printing of blanks for many classes of service, and I mention the printing of one-piece window envelops simply by way of illustration and not as a matter of limitation.

As the printed sheets come off from the press they are wet or damp, and, consequently, if they were to be stacked up with-

out taking special precautions to protect them, the printed matter of one sheet would 55 blur or smut against the adjacent sheets. It is, therefore, desirable to place smut sheets in the stack alternately with respect to the freshly printed or wet sheets, so that when the stack is finished, it will be built up 60 alternately from the wet sheets and the smut sheets. The smut sheets may be of any suitable material, such, for example, as pasteboard, corrugated paper, blotting paper, etc.

It has heretofore been the custom in carrying forward this work to make use of manual labor for placing the smut sheets in position on the pile or stack between the consecutive deliveries of the printed sheets.

In carrying forward many classes of 70 printed work it is quite desirable to allow the stack or pile thus constructed to stand for a certain period of time in order to allow the printed sheets to dry. Thereafter the stack or pile is to be distributed, the 75 dried sheets being removed and sent to a desired destination, and the smut sheets being used in the construction of a new stack is placed for this purpose intermediate freshly delivered wet sheets.

It has heretofore been the custom to make use of manual labor for separating the dried sheets from the smut sheets preparatory to delivering the smut sheets so released to those persons who thereafter place them 85 onto the stack or pile which is being freshly constructed. Altogether several persons have been employed at each printing press solely for the purpose of transferring the smut sheets and printed sheets back and forth in 90 the manner above explained.

One of the objects of the present invention is to provide means for automatically constructing a pile composed alternately of freshly printed sheets or wet sheets and intermediate smut sheets, the said sheets being relatively so positioned that the perforations of the smut sheets will come into registry with the oiled or printed spots of the wet sheets (in case perforated smut sheets 100 be used).

Another object of the invention is to provide mechanism whereby the foregoing results may be obtained, and wherebv the smut sheets so used may be taken directly from 105 a previously constructed stack or pile, the

dried sheets of the said stack or pile being properly delivered to whatever point or mechanism may be decided upon.

More particularly another object of the 5 invention is to provide mechanisms whereby the foregoing results may be obtained by the use of vacuum suction or lifting devices for removing the top sheets from the dry pile.

Other objects and uses of the invention 10 will appear from a detailed description of the same which consists in the features of construction and combinations of parts hereinafter described and claimed.

In the drawings:

15 Fig. 1 is a side elevation of a machine embodying the features of the present invention;

Fig. 2 shows a plan view corresponding to Fig. 1;

20 Fig. 3 shows a front end elevation corresponding to Fig. 1;

Fig. 4 shows a back end elevation corresponding to Fig. 1;

25 Fig. 5 shows diagrammatically the positions of the main operative parts at the commencement of a cycle of movements, a freshly printed sheet having just been placed on the sticks preparatory to delivery by said sticks to the wet stack. In this figure a dry sheet is being withdrawn or delivered by the delivery rolls;

Fig. 6 is a view corresponding to Fig. 5, the sticks having commenced their rearward travel, the smut sheet pick-up having moved 35 down against the exposed smut sheet on the dry stack, and the delivery of the dry sheet continuing;

Fig. 7 is a view similar to Fig. 6, the sticks having continued their travel toward the 40 rear, the smut sheet pick-up having commenced to raise the smut sheet, and the delivery of the dry sheet still continuing;

Fig. 8 is a view similar to Fig. 7, with the exception that the sticks have reached practically their rearmost position, the wet sheet 45 delivery fingers have taken position to grasp the wet sheet, the smut sheet fingers have taken position to grasp the smut sheet, the delivery of the dry sheet has been completed, 50 and the dry sheet pick-ups have started to move down;

Fig. 9 is a view similar to Fig. 8, with the exception that the wet sheet fingers have taken hold of the wet sheet, the positioning 55 fingers on the sticks have released the wet sheet, and the smut sheet fingers have taken hold of the smut sheet;

Fig. 10 is a view similar to Fig. 9, with the exception that the carriage and sticks 60 have started to travel back, and the dry sheet pick-ups have dropped down against the exposed dry sheet;

Fig. 11 is a view similar to Fig. 10, with the exception that the carriage and sticks

have traveled approximately half way back, 65 the wet sheet being delivered onto the stack, the smut sheet being drawn over into position above the stack, and the dry sheet being raised away from the dry stack;

Fig. 12 is a view similar to Fig. 11, with 70 the exception that the wet sheet has been completely deposited on the stack, the smut sheet being fully positioned above the stack, and the delivery of the dry sheet is being commenced;

Fig. 13 is a view similar to Fig. 12, with the exception that the smut sheet has been deposited on the wet stack, and the parts have assumed almost their initial position shown in Fig. 5;

Fig. 14 is a view of the cam block for operating the smut sheet pick-ups;

Fig. 15 is a view of the cam for operating the smut sheet bar;

Figs. 16 and 17 are views of the cams for 85 operating the wet sheet grips so as to give the peculiar motion which will be presently explained; the cam shown in Fig. 16 gives the horizontal component of movement, and the cam shown in Fig. 17 gives the vertical 90 component of movement;

Fig. 18 is a view of the cam for operating the dry sheet pick-ups;

Fig. 19 is a view of the cam for operating the delivery rolls;

Fig. 20 is a view of the cam for operating the air control for the smut sheet pick-ups;

Fig. 21 is a view of the cam for operating the air control for the dry sheet pick-ups;

Fig. 22 is a fragmentary assembly view of 100 the wet sheet grips, the smut sheet grips, the sticks, the smut sheet pick-up, and the wet sheet positioning fingers, the carriage standing at substantially its rearmost position;

Fig. 23 is a view similar to Fig. 22, with 105 the exception that the carriage is near its initial position, and the smut sheet pick-ups are lowered into position against the dry pile;

Fig. 24 is a fragmentary detail of certain 110 of the operating mechanisms for the smut sheet grips;

Fig. 25 is a fragmentary detail of certain 115 of the operating mechanisms for the wet sheet grips;

Fig. 26 is a fragmentary detail of one of the air valves and the immediately adjacent parts;

Fig. 27 is a view corresponding to Fig. 26 except at right angles thereto;

Fig. 28 is a fragmentary assembly view of 120 the dry sheet pick-ups and delivery rolls and the immediately adjacent parts;

Fig. 29 is a fragmentary plan view showing an assembly of the clutch, brake, and reduction gearing for controlling the movements of the tables or platforms;

Fig. 30 is a view taken on the line 30—30

of Fig. 29 looking in the direction of the arrows; and

Fig. 31 is a side elevation of the arrangement of gears whereby it is possible to secure very fine changes or adjustments in the gear reduction ratio.

In the several figures, I have shown the features of this invention as being applied to or used in conjunction with a printing 10 press of the ordinary type, although, as I have previously explained, they may be used in conjunction with any suitable form of printing press and for many other classes of service than that particularly explained 15 herein. This printing press includes a carriage having a cross bar 35, end pieces 36 and 37 provided with rollers 38 traveling on the rails 39 and 40. This carriage also has the wet sheet sticks 41 on which the freshly 20 printed wet sheets lie as they are delivered from the rolls. There is nothing particularly new in this construction but the same has been adapted to the requirements or needs of the present combinations. Suffice 25 it to state at this point that the carriage travels back and forth, the sticks 41 receiving a wet sheet from the printing roll as they reach their extreme right-hand position as compared to Fig. 2, being that position in 30 which they stand closest to the printing roll, after which they travel back to the left as compared to Fig. 2, preparatory to delivering the wet sheet to the wet sheet stack.

Before proceeding to detailed description 35 of the particular mechanisms herein disclosed, I will first have reference to the diagrammatic Figs. 5 to 13 inclusive, in which the main operative parts are shown diagrammatically in a series of consecutive positions. From an understanding of the relative movements herein depicted, the functions and purposes of the particular mechanisms will be better understood.

The sticks heretofore mentioned are designated by the numeral 41 in the several figures. The dry stack and the wet stack are designated by the numerals 42 and 43 respectively. These are built up from the paper sheets and the smut sheets 44 and 45 respectively, these sheets coming alternately in the several stacks. The wet sheet stack 43 occupies a position closer to the printing press than does the dry sheet stack 42, this arrangement being illustrated because of the 50 convenience of the transfer of the various sheets which is thereby secured. As a matter of fact also, the machine herein illustrated is of sufficient width to accommodate two wet sheet stacks side by side and two dry sheet stacks side by side, the same being designated 42 and 42^a and 43 and 43^a in the plan view of Fig. 2.

Mounted on the reciprocating carriage 35 is a set of fingers 46 which can be raised and

lowered with respect to the ends of the sticks 65 41, this raising and lowering being effected by the rocking of a shaft 47. The fingers travel with the carriage and sticks and when they are lowered into the position shown in Figs. 5, 6, 7, 8, and 13, they serve to accurately position the newly delivered wet sheet 70 on the sticks, so that said sheet will bear the proper position when it is delivered over the wet sheet stack.

These fingers 46 are raised near the back 75 end of the stroke of the carriage 35, so that the wet sheet can be gripped and delivered onto the wet sheet stack. This gripping action is secured by a gripping device designated in its entirety by the numeral 48. The 80 same has the sets of relatively movable fingers 49 and 50 which, while traveling together, can be opened and closed for the purpose of gripping the wet sheet at the proper time and in the proper manner. 85

In Fig. 8 the fingers are just grasping the freshly delivered wet sheet; in Fig. 9 the fingers have grasped said wet sheet; and in said figure the fingers 46 have been raised to permit the wet sheet to be drawn off from 90 the sticks.

The wet sheet grippers 48 have a peculiar movement in the cycle of operations, the same being shown by the dotted lines 51 and 52 of Fig. 23, the upward movement being 95 shown by the line 51 and the downward movement by the line 52. The elevation of the wet sheet stack 43 may not always remain exactly the same, owing to slight irregularities or inequalities in the rate of 100 lowering the stack as the sheets are delivered thereonto. Therefore, on the upward movement of the grips, they are carried upward in a comparatively direct path of travel 51. After they have gripped the newly delivered 105 wet sheet they move down by way of a very direct path of travel to a point somewhat above the top of the wet sheet stack, leaving a sufficient clearance above said stack for any inequalities in the elevation of the stack, 110 but nevertheless low enough to bring the newly delivered wet sheet below the top ends of the stop fingers 53. Thereafter the grips 48 move back along a practically horizontal line a sufficient distance to cause the edge of 115 the newly delivered wet sheet to strike against the fingers 53, being stopped thereby, and stripped from the grips, so that the wet sheet will fall down onto the stack 43 in the correct position. Thereafter, the wet sheet 120 grips are lowered an additional distance so as to get them out of the way of other operating mechanisms during another portion of the cycle of movements.

There is provided a series of smut sheet 125 pick-ups 54 whose function is to take hold of the smut sheet exposed by the removal of the delivered dry sheet, so that said smut

sheet can be transferred back onto the wet stack which is being constructed. These smut sheet pick-ups have chiefly a vertical movement, although they may travel on the arc of a circle, as shown. There is also provided a smut sheet bar 55 whose function is to act as a support or guide over which the smut sheet travels or is drawn as it is transferred from the dry stack to the wet stack.

10 Ordinarily this bar 55 stands in the lowered position shown in Figs. 5, 6, and 7, so that when the smut sheet pick-ups have raised the smut sheet a certain distance the bar 55 by swinging backwardly will take a position underneath the edge of the smut sheet, as shown in Fig. 8.

There is also provided a series of smut sheet grips 56 which are carried by or actuated with the carriage bearing the crossbar 35, traveling back and forth the full movement of said carriage and in synchronism therewith. These smut sheet grips include the relatively movable fingers 57 and 58 which normally stand in the relatively open position shown in Figs. 5, 6, 7, 12, and 13, but which may be closed at the proper time to grip the edge of the smut sheet, as shown in Figs. 8, 9, 10, and 11. When so gripped the same sheet will be drawn back on the return movement of the carriage, so that it will be positioned over the top of the newly constructed wet stack, as shown in Figs. 12 and 13. During this travel the smut sheet rides over the bar or roller 55.

35 There is also provided a pair of delivery rolls 59 and 60 which can be relatively moved. These rolls normally stand in contact or close together, as shown in Figs. 5, 6, 7, 8, 9, 10, 12, and 13, but they can be momentarily separated, as shown in Fig. 11, to receive between them the edge of a dry sheet, so as to deliver the same. The delivery illustrated is onto the tapes 61 and 62, as shown in Fig. 1. The inner ends of these tapes travel on the rolls 59 and 60 respectively, and thence over other rolls 63 and 64 respectively. The tapes are not necessary for the delivery of many classes of sheets, but when they are used they travel outwardly continuously 50 away from the rolls 59 and 60.

There is also provided a series of dry sheet pick-ups 65 whose function is to take hold of the dry sheet exposed by the removal of a smut sheet from the dry pile and transfer the edge of the dry sheet to a point where it can be gripped between the rolls 59 and 60 so as to be removed by said rolls. The movement of the dry sheet pick-ups is well shown in Fig. 28, by means of the dotted lines 66. During the first portion of the pick-up operation, the movement is chiefly vertical so as to lift the dry sheet away from the stack, after which the movement becomes horizontal so as to transfer the edge of the dry sheet to a point where it will be gripped

by the rolls. By providing the vertical portion of the movement, assurance will be had that the dry sheet pick-ups will operate properly, regardless of slight inequalities in the elevation of the dry pile.

70

Bearing in mind the foregoing description of the main operating parts I will now describe their main functions. Commencing with the position shown in Fig. 5, the carriage there stands in its extreme right-hand or forward position. The positioning fingers 46 are lowered with respect to the sticks 41, the newly delivered wet sheet 44 is lying on the sticks against the fingers 46, and the backward or left-hand movement of the carriage 75 will carry the newly delivered wet sheet over the wet stack 43. In this figure also a dry sheet 44^a is being removed from the dry stack, and in fact this process of removing a dry sheet has proceeded to such an extent that a considerable portion of the next lower smut sheet has been exposed at the right-hand or forward side of the pile. The smut sheet pick-ups 54 are in their raised position, the smut sheet bar 55 is in its lowered position, the wet sheet grips 48 are in their lowered position, and the dry sheet pick-ups are in their raised position adjacent to their rolls 59 and 60.

85

Moreover, the suction of air has been cut off from the dry sheet pick-ups 65, so that the dry sheet is enabled to travel past the said pick-ups without interference.

90

Proceeding to the position shown in Fig. 6, the backward or left-hand movement of the carriage has commenced. The delivery of the dry sheet 44 is proceeding, and the smut sheet pick-ups have been lowered against the exposed edge portion of the next lower smut sheet on the stack 42. Proceeding to Fig. 7, we find that the backward or left-hand travel of the carriage is still proceeding, the wet sheet grips are rising preparatory to taking hold of the wet sheet 44 lying on the sticks 41. Also the smut sheet pick-ups 54 have commenced to rise and raise with them the smut sheet which they engage. The delivery of the dry sheet is still proceeding in Fig. 7.

100

Passing to Fig. 8, we find that the dry sheet has been completely delivered, the carriage has traveled almost to its extreme left-hand or backward position, the wet sheet grips have taken position ready to grip the edge of the wet sheet on the sticks, the smut sheet pick-ups have risen, and the smut sheet bar 55 has moved backwardly to a position underneath the edge of the raised smut sheet. Also in this figure the smut sheet 115

105

grips are ready to take hold of the edge of the raised smut sheet and the dry sheet pick-ups have started to move down into position against the exposed edge of the dry sheet which is next to be delivered.

120

Passing to Fig. 9, we find that the wet

125

130

sheet grips have taken hold of the edge of the wet sheet, the positioning fingers 46 have been raised out of the way, the smut sheet grips 56 have taken hold of the edge of 5 the raised smut sheet, and the dry sheet pick-ups 65 are continuing to descend.

Passing to Fig. 10, we find that the movements have proceeded an additional amount to the extent that the dry sheet pick-ups 10 have come into contact with the exposed portion of the dry sheet on the top of the stack 42, and the suction of air has been cut off from the smut sheet pick-ups 54, so that the smut sheet may be drawn across the face of 15 said pick-ups. Immediately after the lowering of the dry sheet pick-ups 65 into the position shown in Fig. 10, the suction of air is established, so that when said pick-ups are raised the dry sheet will also rise.

20 In Fig. 11, the return movement of the carriage has proceeded to a considerable extent. The wet sheet grips 48 have been holding the wet sheet 44, while the carriage returns, so that the sticks 41 have been pulling away from underneath the wet sheet and allowing it to descend onto the top of the stack 43. Also the smut sheet 45 has been moved forwardly or to the right with the return of the carriage. Also the dry sheet 25 pick-ups 65 have commenced to raise and transfer the edge of the dry sheet to the delivery rolls.

30 In Fig. 12, the carriage has practically reached its return position. The smut sheet 35 is ready to drop onto the top of the wet stack 43, and the delivery of the dry sheet previously raised has commenced.

In Fig. 13, the smut sheet has been dropped down into the top of the stack and 40 the dry sheet is passing between the rolls. Also the positioning fingers 46 have been lowered, so that when the next wet sheet is delivered onto the sticks 41, it will be correctly positioned. A slight additional movement will restore the parts to the relative positions shown in Fig. 5.

The foregoing description of the relative movements or operations of the main operative parts will make clear the functions and 50 mode of operation of the mechanisms of this machine. Certain of the said so-called main operative parts may, in some cases, be eliminated, as, for example, the smut sheet bar 55. However, the various parts hereinbefore referred to and whose functions have 55 been explained, will ordinarily be used, and, at any rate, their use is desirable in order to secure the best operation of the entire ensemble.

60 Furthermore, the exact manner in which the various operative parts are articulated is largely immaterial, inasmuch as it will be evident that many forms of mechanisms might be devised for giving the desired relative movements. Consequently, although I

shall presently explain a particular construction of mechanism for articulating these parts, I wish it understood that I do not limit myself to the said mechanisms except as I may do so in the claims.

Furthermore, the particular form and relative arrangement of the various main operative parts themselves may from time to time be modified or varied, either in the same machine or in different machines, without departing from the principles and mode of operation of this invention. Consequently, I do not limit myself to the particular construction or arrangement of the main operative parts, excepts as I may do 70 so in the claims.

Bearing all of the foregoing facts in mind, I will now proceed to describe more in detail the particular construction of machine and mechanisms herein illustrated, and in 85 so doing I shall, as far as possible, use the same numerals which I have already used for designating the various main operative parts.

The main operative parts are conveniently 90 carried by a frame work comprising a set of upright posts 67, 68, and 69 on each side of the machine. On the upper portions of these posts are mounted the side rails 70 and 71 and the front and rear cross rails 75 95 72 and 73 respectively. Secured to these portions of the frame are the vertical guide posts 74 and 75 in the front of the machine, and 76 and 77 in the rear portion of the machine. The guide posts 74 and 75 are for 100 the table or platform 78 which carries the stacks 43 and 43^a, and the guide posts 76 and 77 are for the platform 79 which carries the stacks 42 and 42^a.

Suitably journaled in the upper side portions of the frame are the longitudinally extending shafts 80 and 81. Mounted on the shaft 81 is a pair of sprockets 82 and 83 for the platform 79 and mounted on the shaft 80 is a pair of sprockets 84 and 85 110 for said platform. Other sprockets 86, 87, 88, and 89 are mounted on the shafts 81 and 80 respectively (the sprockets 87 and 89 being hidden in Fig. 2), all of said sprockets being for the platform 78. Chains 90 pass 115 over the sprockets on the shaft 81, and chains 91 pass over the sprockets on the shaft 80, the lower ends of all of said chains passing over sprockets 92 which are suitably journaled in the lower portion of the 120 frame. By rotating the shafts 80 and 81, these chains travel over their sprockets. The platforms 78 and 79 are provided with lugs or projections 93, best shown in Fig. 1, which are connected to their respective 125 chains in such a manner that the platforms will rise and fall according to the movements of the shafts. The lugs of the two platforms are so connected to their respective chains that one platform rises while the 130

other one falls, the two platforms reaching their extreme upper and lower limits simultaneously.

The cam shaft 94 extends across the lower forward portion of the machine, being suitably journaled for this purpose. Said shaft carries a beveled gear 95 which is driven from a shaft and bevel gear connected to the main operative parts of the printing press in any convenient manner. The power for operating the mechanisms herein described is delivered to the shaft 94 through the bevel gear 95. Suffice it to state at this point that gear 95 should be such that the mechanisms herein described shall go through a complete cycle of movement synchronously with the movements of the printing press from which the sheets are being delivered.

20 Mounted on the shaft 94 is a sprocket 96 for driving the platform chains through suitable control mechanisms. This sprocket connects by a chain 97 with a sprocket 98 on a stub shaft, the other end of which carries a gear 99. (See Figs. 29, 30, and 31). Adjacent to the gear 99 is another gear 100 on the stub shaft, and the other end of which carries a sprocket 101, the sprocket 101 connects to a sprocket 102 of a speed reducing device 103, through the medium of a chain 104. An idler pinion 105 meshes with both of the gears 99 and 100, said idler pinion being carried by a stub shaft 106 which extends through a slot 107 in the frame of the machine. The sole function of the pinion 105 is to transmit power from the gear 99 to the gear 100. The gear 100 operates at a fixed speed ratio with respect to the cam shaft 94 and the speed of the gear 100 will be dependent upon the ratio between the teeth in the gears 99 and 100. By making these gears relatively large and with a large number of teeth, very slight changes of gear ratio between them may be effected by changing one or the other of them, and substituting another gear having one tooth more or less than the gear for which the substitution is made. For example, if the gear 100 has 250 teeth and another gear having 251 teeth is substituted, the ratio will be changed by something like four-tenths of one per cent. The speed changing device 103 drives a clutch 104^a, the other end of which is connected to a shaft 105^a. This shaft in turn carries the sprockets 106^a and 107^a which drive the chains 108 and 109 respectively. These chains in turn drive the chains passing over the pinions 88 and 86 respectively through the medium of the sprockets over which are passed the lower ends of said chains. Consequently, all of the chains are driven through the medium of the speed changing device 103 and clutch 104^a, and the ratio between the cam shaft and the chains 107 and 108 can be modified by the

proper use of the gears 99 and 100. In this way it is possible to bring the total gear ratio into such value that the platforms will respectively rise and fall at the same speed as the speed at which the stacks are built up and torn down.

A jack shaft 110 is connected to the clutch 104 through the medium of the crank arms 111 and 112, so that the clutch is operated by rocking said shaft 110. A brake drum 113 is mounted on the shaft 105. A brake shoe 114 is carried by a pair of arms 115 and 116 on a jack shaft 117, which jack shaft is connected to the crank 112 through the medium of a link 118. The length of the link 118 can be adjusted by threading one end of the link into the cap 119 a greater or less amount. This arrangement is such that when the jack shaft 110 is rocked in the unlocking direction, the brake shoe 114 is brought against the brake drum 113 at practically the same instant that the clutch is unclutched, so that, as soon as the unclutching takes place, the platforms will be supported by the brake so as to prevent the heavy platform from moving down and raising the light platform. There is nevertheless a sufficient amount of play as between the clutch and the brake mechanism to enable the operator to slightly release the brake before the clutch is again engaged so as to enable him to allow the heavy platform to fall and thereby raise the light platform at his will.

In Fig. 1, the platform 79 stands at its lowermost position, and the platform 78 at its uppermost position. A truck 120 carrying the stack 42 has been run onto the platform 79, and a truck 121 was run onto the platform 78 at a time slightly before that depicted in Fig. 1. As the operations proceed from the position shown in Fig. 1, the stack 42 will be torn down, the stack 43 being built up, the platform 79 simultaneously rising, and the platform 78 simultaneously falling. When the stack 42 has been completely torn down and the stack 43 completely built up, the positions of the platforms 79 and 78 will be reversed from those shown in Fig. 1, and the platform 78 will carry the truck 121 fully loaded, whereas the platform 79 will carry the truck 120 empty. At this time the clutch 104 should be disengaged and the brake shoe 114 set so as to lock the platforms in this position. The truck 121 may then be run off from the platform 78, said platform being at the lowermost position, and a new or empty truck 121 may be run into position on the platform 78. We will then have the condition that the platform 79 standing in raised position carries an empty truck, while the platform 78 standing in lowered position also carries an empty truck. If the platform 79 be somewhat heavier than the platform 78, and if

the brake 114 be now released without engaging the clutch, the platform 79 will slowly descend, while the platform 78 simultaneously rises until the positions of said platforms are reversed and brought into substantially the position shown in Fig. 1. The clutch may then be engaged and the platforms will be ready to receive and discharge their respective loads.

- 10 The over-weighting of the platform 79 may be accomplished in any suitable manner as by means of weights placed thereon in case it be found that the platform is not initially of sufficient weight.
- 15 The roll 60 is conveniently journaled in stationary or fixed journals, the roll 59 being carried by swinging arms 122 and 123, best shown in Figs. 2 and 28. A link 124 operates the arm 122 through the medium of a 20 crank 125, best shown in Figs. 1 and 4. The other end of the link 124 connects to one arm of a bell crank 126 in the forward portion of the machine, the other arm of said bell crank connecting by means of a link 127 25 with the cam 128 on the cam shaft 94. The form of the cam 128 is best shown in detail in Fig. 19.

The dry sheet pick-ups 65 are conveniently mounted on a transversely extending rod 129, best shown in Figs. 2, 4, and 28. The ends of this rod 129 are connected to the elbows of the bell cranks 130 and 131 (one of which is best shown in Fig. 28), each of which bell cranks has a long arm 132 and a 35 short arm 133. The long arm of each of these bell cranks is pivoted to the free end of a link 134 rocking on a fixed center 135. The short arm 133 of each of these bell cranks is pivoted at a point 136 to the elbow 40 of a corresponding bell crank 137, one arm 138 of which is pivoted to a fixed center at the point 139, and the other arm 140 of which bell crank 137 connects to an operating link 141.

- 45 There is a bell crank 137 and a corresponding link 141 at each side of the machine, as best shown in Figs. 1, 2, and 4. The links 141 connect to the lower ends of cranks 142 on a relay rod 143 journaled in 50 the frame of the machine. The relay rod 143 carries a crank arm 144, the free end of which is connected by means of a link 145 to one arm of a bell crank 146. The other arm of said bell crank connects by a link 147 55 with a cam 148 mounted on the cam shaft 94. The form of this cam is best shown in Fig. 18.

The smut sheet pick-ups 54 are carried by a rod 149 having its end portions journaled 60 in the machine. A crank 150 on the rod 149 has its free end connected by a link 151 to one arm of a bell crank 152, the other end of which bell crank connects by a link 153 with a cam 154 on the cam shaft 94. The 65 form of this cam is best shown in Fig. 14.

The smut sheet bar 55 is carried by a pair of crank arms 155 and 156 mounted on a rock shaft 157 which is journaled in the frame of the machine. A crank arm 158 (best shown in Figs. 22 and 23) mounted on the rock shaft 157 is connected to one end of a link 159, the other end of said link being connected to one arm of a bell crank 160. The free end of this bell crank 160 connects by a link 161 to a cam 162 on the 75 cam shaft 94. The form of this cam 162 is best shown in Fig. 15.

The wet sheet grips 48 are carried by a rod 163, the ends of which are journaled in arms 164 and 165 (said arms being shown 80 in Figs. 1, 2, and 3). The form of these arms is best shown in Figs. 22 and 23. The upper ends of the arms 164 and 165 are carried by the cranks 166 and 167 respectively, mounted on the rock shaft 168, which is 85 journaled in the frame of the machine. By rocking the shaft 168, the arms 166 and 167 are raised and lowered so as to raise and lower the links 164 and 165. For this purpose, the rock shaft 168 carries a crank 169 90 (best shown in Fig. 1), the free end of said crank connecting by a link 170 with a bell crank 171. The other arm of this bell crank connects by a link 172 to a cam 173 on the cam shaft 94. The form of this cam 173 is 95 best shown in Fig. 17. Consequently, the cam 173 imparts the vertical component of movement to the wet sheet grips.

A link 174 has one end pivoted to the central portion of the bar 164, the other end of 100 said link 174 connecting to one arm of a bell crank 175. The other arm of the bell crank connects by a link 176 to a cam 177 on the cam shaft 94. The form of the cam 177 is best shown in Fig. 16. Consequently, the 105 cam 177 imparts horizontal components of movement to the wet sheet grips. In order to deliver this movement uniformly to both ends of the bar 163 through the medium of both of the bars 164 and 165, I have provided a relay from the bar 164 to the bar 165, the same being best shown in Fig. 2. This relay comprises the link 178 extending from the bar 164 to a crank 179 on a rod 180 journaled in the frame of the machine. 110 On the other end of the rod 180 is another crank 181 which connects by a link 182 to the central portion of the bar 165, for the purpose specified.

The dry sheet pick-ups and the smut sheet 120 pick-ups may be of any suitable type and construction. As a matter of convenience, I have illustrated the same as comprising vacuum cups, so that upon the application of suction to these cups, the dry sheets and 125 smut sheets will be taken hold of and lifted from the pile. The construction of the dry sheet pick-ups is best shown in detail in Fig. 28. The pick-ups 65 are in the form of hollow cups having rubber contact rims or sur- 130

- faces 183. Each of the hollow cups 65 is carried by a pin or rod 184 working within a cylinder 185, which cylinders in turn are connected to the rod 129 and carried thereby.
- 5 The springs 186 within these cylinders tend to press the pins and vacuum cups downwardly, the amount of such movement being limited by the nuts 187 on the rods 184. The movement thus provided for is sufficient to take care of inequalities in the elevation of the dry pile, so as to insure a flat firm contact of the vacuum cups against the upper sheet of the pile regardless of such slight variations in elevation.
- 10 15 The rod 129 is conveniently hollowed, so that it really constitutes a pipe through which the vacuum is delivered to the several cups 65 through the flexible hose connections 188. This hollow pipe 129 is in turn connected to suitable vacuum apparatus through the medium of the valve control now to be explained. One of these valve control mechanisms is shown in detail in Figs. 26 and 27. The same comprises the pipe 189 leading from the vacuum apparatus, and pipe 190 leading to the vacuum cups. A valve 191 is placed between the pipes 189 and 190, said valve being operated by the stem 192. Another valve 193 also connects to the pipe 190 leading to the vacuum cups, said valve 193 being operated by the stem 194. A link 195 has one end pivoted to a stationary part at the point 196, its free end directly engaging the pin 194 and also being connected to a link 197. This link in turn connects to the free end of a lever 198 pivoted to a stationary part at the point 199 and engaging the pin 192. A spring 200 normally rocks both of the levers 195 and 198 against the force of a cam driven by the cam shaft 94. One of these cams is provided for the vacuum cups of the dry sheet pick-ups, and another one for the vacuum cups of the smut sheet pick-ups. These cams are shown in detail in Figs. 21 and 20 respectively, and they are numbered 201 and 202 respectively.
- 15 20 25 30 35 40 45 The valves 191 and 193 operate in opposition, one of them opening at the instant of the closing of the other. The valve 191 establishes the vacuum, the valve 193 breaking the same. This valve 193 may open directly to atmosphere, or it may be connected through the medium of a pipe 203 to a compressed air apparatus, so that at the very instant the vacuum is shut off by the closing of the valve 191, compressed air will be applied by the opening of the valve 193 so as to give an instant release of the dry sheets or the smut sheets, as the case may be.
- 50 55 60 The construction of the smut sheet pick-ups is best shown in detail in Figs. 22 and 23. The vacuum cups 54 therein illustrated are provided with the rubber contact surfaces 204, and said vacuum cups are carried by the arms 205 freely mounted on the hol-

low shaft 149. Adjacent to each of the arms 205 is a pair of fingers 207 and 208 on the rock shaft 149. A spring 209 works between the finger 207 and a lug 210 on the arm 205 so as to force said arm down until the lug 210 engages the finger 208. This arrangement gives a sufficient amount of lost motion or play in the vacuum cups to compensate for inequalities in the elevation of the dry stack.

75 The construction of the wet sheet grips is best shown in detail in Figs. 22, 23, and 25. I have already explained that the rod 163 is carried by the arms 164 and 165. Each of the grips comprises a finger 211 fixed on the rod 163 and having a spring tip 50. Another rod 213 is journaled in the bars 164 and 165, said rod 213 carrying a series of blocks 214 having the spring tips 49 corresponding to the spring tips 50. By rocking the rod 213 80 the spring tips will be respectively engaged and disengaged. This rocking is accomplished by the mechanism shown in detail in Fig. 25. The same includes a crank finger 216 on one end of the rod 213 in conjunction with a cam block 217 pivoted on the point 218. A crank finger 219 connects to the cam block 217 and carries a pin 220. A spring 221 normally holds the cam block 90 and crank pin 220 in the position shown in Fig. 25. Mounted on the carriage 35 is the rock shaft 47. On this rock shaft is mounted a finger 223, the outer end 224 of which normally stands in such position that, as the carriage travels backwardly, the finger 224 will engage the pin 220 near the rear end of the travel, thereby rocking the pin 218, forcing the cam 217 against the finger 216, rocking the shaft 213, and thereby moving the fingers 49 away from the fingers 50. The wet sheet grips are thus opened just before the back limit of movement is reached, and in time to permit the edge of the wet sheet to enter between the jaws of the wet sheet grips.

105 110 115 120 125 130 Mounted on the shaft 47 is a hook finger 225 (best shown in Fig. 22). A hook finger 226 is mounted on a stationary part in position to coöperate with the finger 225, a spring 227 normally holding the finger 226 in raised position. The arrangement is such that, as the carriage completes its backward movement and reaches its extreme limit, the finger 225 snaps over the finger 226, so that the instant the carriage commences its return movement, the hook finger 225 will be held momentarily by the finger 226, thereby rocking the shaft 47 and raising the finger 223 away from the pin 220. This will permit the spring 221 to restore the cam block 217, permitting the shaft 213 to rock back and instantly close the wet sheet grips. A pair of coiled springs 228 serve to rock the shaft 213 so as to close the grips in the manner just explained.

It was previously explained that, as the extreme limit of travel of the carriage 35 is reached, the fingers 46 must be raised, so as to release the wet sheet and permit the same 5 to slide over the ends of the sticks 41. This lifting of the fingers 46 is conveniently accomplished by mounting them on the shaft 47, so that when said shaft is rocked by the engagement of the finger 225 with the finger 10 226, the fingers 46 will be raised. A spring 229 mounted on the carriage 35 has a bent or notched portion 230 adapted to engage with a lock 231 mounted on the shaft 47, so as to hold said shaft in the rocked position 15 shown in Fig. 22. Mounted on said shaft is also a cam finger 231 adapted to engage a fixed pin 232 near the extreme return limit of movement so as to restore the rock shaft 47 to its closed position. The pin 232 is 20 best shown in Fig. 5.

The construction of the smut sheet grips 56 is best shown in Fig. 24, and as previously explained these grips include the fingers 57 and 58. The fingers 58 are fixed on the carriage 35 being conveniently connected to a channel 233 on the carriage. Mounted on the carriage is a rock shaft 234 to which are connected the smut sheet grip fingers 57. A spring 235 normally rocks the shaft 234 into 30 the position shown in Fig. 24 so as to close the fingers 57 against the fingers 58.

Mounted on the shaft 234 is a notched block 235^a, having the notch 236. A dog 237 is pivoted to another portion of the carriage at the point 238, a spring 239 tending to carry the dog 237 under the notch 236. A crank finger 240 is mounted on the shaft 234, the lower end of said crank finger 240 having a pin 241 which is adapted to be engaged by a stop 242 on the frame of the machine located at the point shown in Figs. 12 and 13. This stop 242 stands in such position that the crank finger 240 is rocked so as to rock the shaft 234 slightly before the carriage reaches its extreme limit of movement to thereby permit the dog 237 to fall under the notch 236 and hold the fingers 57 away from the fingers 58. The carriage will then complete its return movement a sufficient distance to permit the fingers 58 to pull away from the edge of the smut sheet, said sheet falling onto the top of the wet pile.

Connected to the dog 237 is a crank finger 243 having a pin 244 which is adapted to engage a stop on the frame of the machine just about the time that the carriage reaches the extreme forward limit of its movement. This engagement takes place after the edge 60 of the next smut sheet has entered between the fingers 57 and 58, so that when the engagement finally takes place, said smut sheet will be gripped by the releasing of the dog 237 from the notch 236.

65 It is believed that the operation and func-

tions of the various parts of this machine will be readily understood and appreciated from the preceding explanation. I wish to point out, however, the fact that the features of this invention are not limited in their application to use with printing presses and the like, and that in illustrating and describing them in such a use, I do so simply by way of an example or illustration. It is, however, to be observed that the features 70 bear a peculiar relationship to this particular application, since a machine of this kind is particularly desirable for use in the printing of the sheets from which window envelopes are to be made. Furthermore, the 80 features of the invention do bear a peculiar relationship to use in connection with printing presses, because the operations of the present machine should be conducted synchronously with respect to the operations of 85 the printing press.

It is to be observed that as soon as the vacuum is supplied to the various cups through the vacuum controlling valves, the smut sheets and dry sheets will be alternately lifted from the dry sheet pile or stack the dry sheets being sent to the delivery rolls and the smut sheets being returned to the new or wet sheet stack. If, for any reason, the printing press should fail to deliver a 95 wet sheet at the proper time onto the sticks 41, we would have the condition that two smut sheets would be consecutively placed on the wet sheet stack. Consequently when said stack was afterward placed on the platform 79, the dry sheet pick-ups would deliver a smut sheet to the delivery rolls and the operation of bearing down the dry stack would become reversed from that time forward.

Ordinarily the cylinder printing press is provided with means for raising the cylinder under the control of the operator, so that when the operator sees that a sheet has failed to deliver onto the cylinder, he can 105 lift the cylinder so as to interrupt the printing operation. It is, therefore, desirable to provide an operative connection from this lifting mechanism to the valves for the vacuum cups, so that when the operator thus 110 interrupts the operation of the printing mechanism he will simultaneously interrupt the travel of vacuum and thus prevent the delivery of a smut sheet to the delivery rolls in the manner above explained.

I wish also to point out the fact that I do not limit myself to the particular construction and arrangement of mechanism hereinabove explained and described, except as I may limit myself in the claims.

I claim:

1. The combination with a printing press of a reciprocating carriage for the delivery of printed sheets therefrom, a vertically movable wet stack platform adjacent to the 130

delivery point of said carriage, a vertically movable dry stack platform adjacent to the wet stack platform, means for simultaneously raising the dry stack platform and lowering the wet stack platform at equal speeds, a pair of delivery rolls adjacent to the position of the dry stack platform, means adjacent to the position of the wet stack platform for grasping the edge of a wet sheet during the last portion of the forward travel of the carriage for the purpose of preventing a return of said sheet with the carriage, a set of vertically movable vacuum cups mounted in a position to engage the edge of a smut sheet lying on the top of the dry stack, means for supporting the smut sheet so raised in elevated position, means on the carriage for grasping the edge of said smut sheet and drawing the same over the supporting means to a position on top of the wet stack, a set of vertically movable vacuum cups adapted to engage the exposed edge of a dry sheet lying on top of the dry sheet stack to raise the same into position for engagement by the delivery rolls, and means operating in timed relationship with respect to the printing press for operating all of said parts in the sequence specified, substantially as described.

2. The combination with the sheet delivery carriage of a printing press or the like, of a wet sheet stack support adjacent to the delivery position of said carriage, a dry sheet stack support adjacent to the wet sheet stack support, dry sheet delivery means adjacent to the wet sheet stack support, means for grasping the edge of a wet sheet when the carriage is near the forward extreme of its travel to transfer the same to the top of the wet sheet stack, means for raising the edge of a smut sheet on top of the dry sheet stack, means for supporting the smut sheet when so raised, means on the carriage for grasping the edge of the smut sheet and drawing the same over said support during the return movement of the carriage, means for raising the exposed edge of a dry sheet on top of the dry sheet stack and transferring the same to the delivery rolls, and means for operating all of said parts in timed relationship with respect to the operation of the printing press for the purpose specified.

3. The combination with a printing press having a wet sheet delivery carriage, of a wet sheet stack support, a dry sheet stack support, means for transferring a wet sheet from the carriage to the wet sheet stack, means for raising the smut sheet exposed on top of the smut sheet stack, means for supporting the smut sheet so raised, means on the carriage for grasping the smut sheet so raised and drawing the same over said support during the return movement of the

carriage to transfer the same to the wet sheet stack, means for raising and delivering a dry sheet from the top of the dry sheet stack, and means for operating all of said parts in timed relationship with respect to the operation of the printing press, substantially as described.

4. The combination with a printing press or the like, of a wet sheet stack support, a dry sheet stack support, means for delivering a wet sheet stack from the printing press to the wet sheet stack, means for raising a smut sheet from the top of the dry sheet stack, means for supporting the smut sheet so raised, means for transferring the smut sheet so raised over said support to the wet sheet stack, means for raising and delivering a dry sheet from the top of the dry sheet stack, and means for operating all of said parts in timed relationship with respect to the printing press, substantially as described.

5. The combination with a printing press, of a wet sheet stack support, a dry sheet stack support, means for transferring a wet sheet from the printing press to the wet sheet stack, means for transferring a smut sheet from the dry sheet stack to the wet sheet stack, means for transferring a dry sheet from the dry sheet stack, and means for operating all of said parts in timed relationship with respect to the printing press, substantially as described.

6. The combination with a printing press, of a wet sheet stack support, a dry sheet stack support, means for transferring a wet sheet from the printing press to the wet sheet stack, means for thereafter transferring a smut sheet from the dry sheet stack to the wet sheet stack, means for delivering an exposed dry sheet from the dry sheet stack, and means for operating all of said parts in timed sequence with respect to the operations of the printing press, substantially as described.

7. The combination with a printing press, of means for transferring a wet sheet from the printing press to a wet sheet stack, means for thereafter transferring a smut sheet from a dry sheet stack to the wet sheet stack, means for delivering an exposed dry sheet from the dry sheet stack, and means for operating all of said parts in timed sequence with respect to the operations of the printing press, substantially as described.

8. The combination with a printing press or the like, of means for transferring a wet sheet from the printing press to a wet sheet stack, means for thereafter transferring a smut sheet from a dry sheet stack onto the wet sheet so transferred, means for delivering a dry sheet exposed by said transfer of the smut sheet, and means for operating all of said parts in timed sequence with respect

to the operations of the printing press, substantially as described.

9. The combination with a printing press or the like, of a vertically movable wet sheet stack platform, a vertically movable dry sheet stack platform, means for causing said platforms to simultaneously move in opposite directions at equal speeds during the operation of the printing press, means for at 10 times connecting said moving means to the printing press for the purpose of causing the platforms to move in definite relationship with respect to the printing press, and means for at times making inoperative said 15 means and locking the platforms against movement, substantially as described.

10. The combination with a printing press or the like, of means for transferring a wet sheet from the printing press to a wet sheet 20 stack, vacuum cups for engagement with the exposed surface of a smut sheet on a dry sheet stack, means for transferring a smut sheet so engaged to the wet sheet stack, vacuum cups for engagement with the ex- 25 posed surface of a dry sheet on the dry sheet stack, and independent means for placing both of said sets of vacuum cups in communication with suitable vacuum apparatus during the times of their engagement with 30 their respective sheets, substantially as described.

11. The combination with a printing press or the like, of a wet sheet stack support, a dry sheet stack support, means for transferring a wet sheet from the printing press to a position above the wet sheet stack, wet sheet grips for engaging the exposed edge of said wet sheet, means for thereafter lowering the said grips and stripping the 40 wet sheet therefrom, means for transferring a smut sheet from the dry sheet stack, and means for transferring a dry sheet from

the dry sheet stack, substantially as described.

12. The combination with a printing press 45 or the like, of means for transferring a wet sheet from the printing press to a position above a wet sheet stack, suitable wet sheet grips for engaging the edge portion of said wet sheet, and for thereafter stripping the 50 wet sheet from the grips and depositing the same upon the stack, means for transferring a smut sheet from a dry sheet stack to the wet sheet stack, and means for transferring a dry sheet from the dry sheet stack, sub- 55 substantially as described.

13. The combination with a printing press or the like, of wet sheet stack and dry sheet 60 stack supports, means for transferring a wet sheet to the wet sheet stack, means for transferring a smut sheet from the dry sheet stack, and means for thereafter transferring a dry sheet from the dry sheet stack, said transferring means being operable at different elevations of the wet and dry sheet 65 stacks, substantially as described.

14. The combination with a printing press or the like, of wet sheet stack and dry sheet 70 stack supports, means for transferring a wet sheet to the wet sheet stack, means for transferring a smut sheet from the dry sheet stack, and means for transferring a dry sheet from the dry sheet stack, substantially as described.

15. The combination with a printing press 75 or the like, of means for transferring a wet sheet from the printing press to a wet sheet stack, means for transferring a smut sheet from a dry sheet stack to the wet sheet stack, and means for thereafter transferring a dry 80 sheet from the dry sheet stack for delivery to a distant point, substantially as described.

ERNEST W. SAUERMAN.
